UNITED STATES PATENT OFFICE.

JOSEPH LINDLE, OF CHICAGO, ILLINOIS.

REFRIGERATOR.

SPECIFICATION forming part of Letters Patent No. 354,916, dated December 28, 1886.

Application filed July 12, 1886. Serial No. 207,742. (No model.)

To all whom it may concern:

Be it known that I, JOSEPH LINDLE, a citizen of the United States, residing at Chicago, Illinois, have invented certain new and useful Improvements in Ice-Boxes and Refrigerators, of which the following is a specification.

In the drawings, Figure 1 is a longitudinal vertical section of the refrigerator or ice-box with the parts in place. Fig. 2 is a perspective view of the water and filtering chambers, and Fig. 3 is a perspective view of a modification of the same.

A is the water-chamber, B the filter-chamber, and C the filtered-water chamber.

15 My invention is intended to be an improvement on Letters Patent No. 240,523, of April 26, 1881, No. 320,483, of June 23, 1885, and No. 320,484, of June 23, 1885, issued to me for improvements in water-coolers and refrigerators, and is the result of practical experience in the manufacture and operation of my several inventions.

25 In making a refrigerator containing my present improvements I make, preferably at one end of the same, a water-chamber of any suitable metal or material, and immediately under the same a filtering-chamber to be filled with charcoal or other suitable filtering material. I prefer to have these chambers extend across the end of the refrigerator, as shown in the drawings. I then make a third chamber to contain the filtered water after it has percolated through the charcoal and is ready for use. This third chamber may be 35 placed immediately in front of the filtering-chamber, as shown in Fig. 1, or it may be immediately under the filtering-chamber, as shown in Fig. 2, or it may be under the filtering-chamber and extend out wholly or partially across the bottom of the refrigerator, as 40 shown in Fig. 3 of the drawings. When placed in front of the filtering-chamber, as shown in Fig. 1, the chamber marked E in my Patent No. 320,484 may be dispensed with, and when 45 put under the filtering-chamber, or under and extending out partially or wholly across the bottom of the ice-box, the chamber marked

D in the same patent may be dispensed with. In either case I contemplate the use of only three chambers instead of four, as in that patent. The filtering-chamber is provided with a hole or door through which the filtering material may be inserted, and by means of which it may be renewed or repacked from time to time, as necessary. I have shown this hole or door in the top of the filtering-chamber; but of course it may be located in any other convenient position. The water-chamber is provided with holes or perforations, which convey the water into the filtering-chamber, and the filtering-chamber is also provided with holes or perforations, to carry the water from the filtering-chamber into the filtered-water chamber. From this chamber it may be drawn off for use in any convenient manner.

50 55 60 65 70 75 80 85 90
What I claim as new, and desire to secure by Letters Patent, is—

1. In a refrigerator, a water-chamber, a filtering-chamber provided with a hole or opening through which access may be had to its interior, and a filtered-water chamber immediately in front of the filter-chamber, all of such chambers communicating with each other, substantially as described.

2. In a refrigerator, a water-chamber, a filtering-chamber provided with a hole or opening through which access may be had to its interior, and a filtered-water chamber immediately under the filter-chamber, all of such chambers communicating with each other, substantially as described.

3. In a refrigerator, a water-chamber, a filtering-chamber provided with a hole or opening through which access may be had to its interior, and a filtered-water chamber under and extending out wholly or partially across the ice-space, all of such chambers communicating with each other, substantially as described.

JOSEPH LINDLE.
